J. WEISS

SWIMMING DEVICE

Filed March 19, 1923

INVENTOR
J. Weiss

BY *Marvin Palment*
ATTORNEY

UNITED STATES PATENT OFFICE.

JOHN WEISS, OF POMPTON PLAINS, NEW JERSEY.

SWIMMING DEVICE.

Application filed March 19, 1923. Serial No. 626,013.

To all whom it may concern:

Be it known that I, JOHN WEISS, a citizen of Germany, residing at Pompton Plains, in the county of Morris and State of New Jersey, have invented certain new and useful Improvements in Swimming Devices, of which the following is a specification.

This invention relates to an improvement 10 in swimming outfits and its object is to provide an outfit which may be readily applied to the person of the wearer and which will support the body on the surface of the water.

15 Another object of the invention is to provide propelling means by which it is possible for the user to readily move about from place to place in the water.

With these and other objects in view, 20 which will become more apparent as the description proceeds, the invention consists in the novel construction, combination and arrangement of parts which will be fully set forth in the following description and illustrated in the accompanying drawing, in which:—

Figure 1 is a view of a person equipped with my swimming device.

Figure 2 is a sectional view of the gas 30 generator for producing the float inflating fluid.

Figure 3 is a face view of one of the limb operated propelling devices.

Figure 4 is a sectional view taken on line 35 4—4 of Figure 3.

Figure 5 is a view of one of the swimming gloves.

Referring to the drawing in detail, the numeral 10 designates a belt adapted to encircle the waist of the wearer, and secured to said belt is a housing 11 provided with a horizontal partition wall 12 forming a liquid containing chamber 13 and a gas generating chamber 14.

45 Formed at opposite ends of the gas generating chamber are gas outlet openings 15 and 16 and threaded bosses 17 project outwardly from the end walls in alignment with the openings, providing means for attaching the float inflating tubes to the chamber.

The liquid containing chamber 13 is provided with a filling opening fitted with a closure plug 18 and formed in the partition wall 12 is a valved opening 19 through 50 which the liquid is admitted to the chamber

14, where it contacts with a gas forming material, such as calcium carbide or the like.

As shown in detail in Figure 2, the valve 20 closing the opening 19, is provided with a valve stem 21 extending through the upper wall of the housing 11 and is formed with a head 22 which provides a handle, pressure upon which will open the valve.

This valve is normally retained in closed position by a spring 23, one end of which bears on a collar 24 on the valve stem, while its opposite end engages the U-shaped yoke 25.

Extending through the chamber 13 and communicating with the chamber 14 is a filling tube 26 fitted at its upper end with a closure plug 27 by which the escape of gas generated in the chamber 14 is prevented.

Connected to the bosses 17 are tubes 28 leading to hollow globular expansible chambers 29 and 30, attached to the belt 10 by snap hooks constituting flexible connections 31 and provide floats by means of which the device is given its buoyancy.

In order that the user may readily propel himself, gloves 32 are provided, and are formed between the fingers 33 with web 34.

Further propelling means are provided in the form of plates 35, the side edges of which converge toward one end and are provided with eyes 36 for the reception of securing straps, by means of which the device is attached to the limbs of the user.

A longitudinal reenforcing strap 37 provided with eyes 38 is secured to one face of each plate 35 centrally between its converging edges, and pivoted at spaced intervals as at 39 to the opposite face of the plate 35 are feathering vanes 40 provided with stops 41 which limit their movements in one direction.

In use the belt 10 is strapped about the waist of the user and pressure applied to the head 22, thereby admitting water to the gas chamber 14, where it contacts with the gas producing material and creates a fluid of less specific gravity than water, which enters the floats 29 and 30 through the tubes 31, thereby inflating the same, so as to support the wearer on the surface of the water.

Assuming that the gloves 32 and plates 35 have been properly adjusted, it will be

seen that the user may readily propel himself about.

While in the foregoing there has been shown and described the preferred embodiment of this invention, it is to be understood that minor changes in the details of construction, combination and arrangement of parts may be resorted to without departing from the spirit and scope of the invention as claimed in the appended claim.

What I claim and desire to secure by Letters Patent, is:—

A swimming device comprising a waist

belt, a gas generator attached thereto, 15 means for supplying said generator with gas making material, said means being provided with a tight closure, inflatable floats, flexible means connecting the floats with the belt, said floats being removable and independent outlet tubes connecting the generator and floats whereby gas generated in the generator will enter and inflate the floats.

In witness whereof I have affixed my signature.

JOHN WEISS.
